UNITED STATES PATENT OFFICE.

WILLIAM F. GARDNER, OF WASHINGTON, DISTRICT OF COLUMBIA.

TIME CONTROLLING AND CORRECTING SYSTEM.

SPECIFICATION forming part of Letters Patent No. 335,186, dated February 2, 1886.

Application filed March 31, 1885. Serial No. 160,765. (No model.)

To all whom it may concern:

Be it known that I, WILLIAM F. GARDNER, a citizen of the United States, residing at Washington, in the District of Columbia, have 5 invented certain new and useful Improvements in Time Controlling and Correcting Systems, of which the following is a specification, reference being had to the accompanying drawings.

My invention relates to a system for automatically controlling clocks, and sending time-signals, and is an improvement on the system granted to me in Letters Patent Nos. 287,015 and 307,287.

The invention consists, first, in an auxiliary 15 clock-plate having a seat for the magnets; second, in an adjustable magnet, armature-lever, and secondary controlling-springs; and, third, in means for automatically giving a sound or signal at the instant of the action of 20 the controlling mechanism.

It further consists in certain details of construction, arrangement, and operation of the several parts, as will be hereinafter more fully set forth in the specification, and pointed out 25 in the accompanying drawings, in which—

Figure 1 is a perspective view of my device; Fig. 2, a front elevation of same; Fig. 3, a front elevation, partly in section, of same; Fig. 4, a detail perspective view of the same and the 30 shouldered arbor of the minute-hand, and Fig. 5, a detail side elevation of the shouldered arbor, adjustable friction-spring, and bridge-plate; Fig. 6, a perspective view of the device for producing the audible signal.

The action of the magnets, the armature-lever, and the correcting mechanism does not differ from that described in the patents above referred to.

In the present instance the actuating-bar I, 40 with the rings I², is struck up from a single piece of metal, the push-points P P' being secured thereto. The point P' has a slot, z, in which the set-screws z' enter, and by means of which the point is rendered adjustable on the bar. The upper end, i⁵, of the bar is given 45 a half-twist, so as to bring the points i at right angles to the line of direction of the armature-lever. The push-bar is raised above the front plate, k, of the clock by means of the guide-blocks a a', the lower end of said bar passing through the lower guide-block, whereby verticality of the bar is insured and slipping pre-

vented. The dial-train does not differ from that shown in my former patents, except that a double bridge-plate, J, is placed on the front 55 plate, k, of the clock.

In my Patent No. 307,287 the push-points were cut away at the end on their inner face, so as to leave the outer and lower portions flat, and the inner parts curved to fit the groove at the 60 top of the cam, the points centering with the center of the cam, the flat part extending slightly beyond the outer face of the cam, so both the flat part and the point should strike the ledge and the cusp of the cam simultaneously. 65

In the present instance the minute-hand arbor Q is cut away, as at n², Fig. 4, so as to leave a flat surface on said arbor, similar to the lip or flat ledge on the cam, as just described. This cut-away part may be in front or in the rear of the cam. In Fig. 3 I have shown it in front of the cam and in Fig. 4 in rear thereof. I prefer, however, to have it in the rear of the cam. In this construction the 75 lip i of the push-point strikes squarely against the shoulder n² at the same instant that the projecting point enters the cusp in the cam F. I thus prevent any forward or backward movement of the cams and hands and arrive 80 at an exact zero-point at the instant of the correcting-signal.

The sleeve Q', which slips over the minute-hand arbor Q, passes through the front plate, k, and has a flange, n³, which bears against the 85 friction-spring M. A double foot-bridge plate, J', attached to the rear of the front plate, k, supports the arbor Q, and gives room between the points of attachment for the friction-spring to move freely therein. The plate M', Fig. 5, 90 prevents the spring M from slipping and exerts friction on the arbor, as in Patent No. 307,287.

It is not deemed necessary to describe the action of the cam push-bar, as it does not differ from that described in my former patent. 95

In order to obtain adjustability of the magnets B and the armature-lever, so as to regulate or obtain a proper throw or stroke upon the cam-bar, it has been found more convenient to remove the magnets from the back plate, K, where they were located in my former patents. I have now provided a back supporting-plate, k², to which the entire clock-move-

ment is secured by the posts *p*. At one side of said back plate is an extension, *k*³, which turns downwardly and then horizontally outward, as at *k'*, forming a supporting plate or 5 table longitudinally slotted, as at *k'*. The plate *N* of the magnets *B* (but one of which is here shown) is mounted on the table *k'*. A set-screw, *O*, enters plate *N* between the magnets, and permits said magnets to be moved along 10 the slot *k'*, and be clamped or fastened in any required position.

In Fig. 2 not only the magnets, but the post *A* and insulated contact-support *C*, are adjusted back and forth in the slot. The object of this 15 adjustment is to regulate the distance of the magnets from the armature, and thus regulate the vertical movement or throw of the lever *A'*. This enables me to obtain the exact and vertical action of said lever upon the cam-bar, 20 and prevent undue strain upon said bar. The insulated support *C* and its contact-springs *b* *b'* form the secondary transmitter.

It will be observed that the core of the magnets must be directly and centrally beneath 25 the center of the armature, so as to obtain the full and direct action of the magnets when energized. By means of the slot *k'* in the table I am enabled to turn the magnets around in 30 the slot slightly, but sufficiently for this purpose.

Sometimes when the variation or correction is very small the movement of the hands backward to the zero-point is hardly perceptible, and in my former patents there was nothing 35 to verify the sight but the slight sound given out by the downstroke of the armature-lever and cam-bar. It is desirable to have the ear act in unison with the eye for the verification of the setting or correcting signal. To this 40 end I have provided an audible signal, preferably a bell, located outside of the clock-case, which bell will be sounded at the instant of the final signal, and by the simultaneous and automatic action of the armature-lever through 45 the intervention of the magnets. The mechanism therefor consists of a lever, *h*, provided with a striking-ball, *h'*. This lever *h* is secured to a bar, *g*, journaled in the front and back plates, *k k'*. To this journaled bar a bent arm, 50 *G*, is secured and engages with the armature-lever *A'* by means of the loop *g'*. The bell *H* is preferably located at the outside and at the upper end of the clock-case, the lever *h* passing through an opening in the case. It is obvious 55 that the bell or indicator may be placed within the case; but in order that the sound or signal be clear and distinct I preferably place the bell on the outside, as shown in the drawings. The bell may be located at the bottom 60 of the clock-case, as shown in Fig. 3. In this case the lever *h* is secured to a pivoted bar, *f'*, to which the lever *f* is also secured. The lower end of the cam-actuating bar strikes against 65 said lever *f* and depresses it. This action causes the bell to be sounded by raising the lever *h*. I may of course use some other form

of signal or indicator than the bell without departing from the spirit of my invention.

The operation of the mechanism is as follows: When the correcting-signal is sent (as in my former patents) and the armature-lever *A'* depressed, it not only pushes down the cam-actuating bar, (which corrects the hands' error, as before described in my former patents,) but at the same time depresses the bent bar 75 *G*, and this, through the intervention of bar *g* and lever *h*, sounds the bell or indicating-signal.

Having thus described my invention, what I claim as new, and desire to secure by Letters 80 Patent, is—

1. In a time correcting and controlling system, a controlled clock in a main line or local circuit provided with a magnet, armature-lever, and error-correcting mechanism for the 85 hands, said lever acting, through the intervention of suitable mechanism, to give an audible signal at the instant of the control, substantially as set forth.

2. In a time controlling and correcting system, a controlled clock provided with mechanism for correcting the clock error, said clock being provided with an audible signal actuated by the correcting mechanism, so as to be automatically sounded at the instant of control, substantially as set forth. 90

3. In a time controlling and correcting system, a clock one or more of the hands' arbors of which are provided with a cam and are cut away to form a flat striking-surface for a lip 100 or ledge on the cam push-point, substantially as set forth.

4. In a time controlling and correcting system, a controlled clock the hands' arbors of which have a flat striking-surface, and a cam 105 secured to said arbor in front or rear of said striking-surface, substantially as set forth.

5. In a controlled clock in a time controlling and correcting system, the combination, with the dial-frame and cam-actuating mechanism, of the hands' arbors, one or more of which are provided with a flat striking-surface, and a cam in front or rear of said flat surface, whereby the cam push-point simultaneously strikes the cam and arbor, and thereby prevents any backward or forward movement of the arbors and hands at the instant of correction, substantially as set forth. 110

6. A controlled clock in a time controlling and correcting system, one or more of the hands' arbors of which are provided with a sleeve, *Q*, having a flange, *n*, against which the friction-spring *M* comes in contact, substantially as set forth. 120

7. In a time controlling system in which 125 the hand of the controlled clock is set by means of a cam on its arbor actuated by a push-bar, the combination, with the front plate, of a bridge-plate in rear thereof, in which is placed the friction-spring which connects 130 the cam to the arbor, substantially as and for the purpose set forth.

8. In a time controlling system, a clock provided with an auxiliary supporting-plate for the clock-movement, said plate having an extension provided with a slotted table to support the magnet, substantially as and for the purpose set forth. 20
9. In a time controlling and correcting system, the combination, with the clock-movement, of the controlling and correcting mechanism, and means of simultaneously adjusting the distance of the magnet from the armature and the vertical movement of the armature-lever, substantially as and for the purpose set forth. 25
- 10 15 10. In a time controlling and correcting system, the combination, with the clock-movement, of the adjustable magnet, armature-lever, and adjustable secondary transmitter, substantially as and for the purpose set forth. 30
11. In a time controlling and correcting system, the combination, with the clock-movement having a hands' correcting mechanism, of an audible signal actuated by the vertical movement of the cam-bar, as set forth. 20
12. In a time controlling and correcting system, a clock provided with means for correcting its error, and an audible signal actuated through the intervention of suitable mechanism by the armature-lever of the correcting mechanism, as set forth. 25

In testimony whereof I affix my signature in presence of two witnesses.
